CLAIM

The ornamental design for a combined vehicle roof interior instrument panel, rear view mirror and sun visors, substantially as shown and described.

DESCRIPTION

FIG. 1 is a front elevational view of the combined vehicle roof interior instrument panel, rear view mirror and sun visors showing our new design;

FIG. 2 is a rear elevational view thereof; and

FIG. 3 is a right side elevational view thereof.

FIG. 1.

FIG. 2.

FIG. 3.
